UNITED STATES PATENT OFFICE.

JAMES CHANTRY, OF SHEFFIELD, ENGLAND.

SHARPENING DEVICE.

Application filed July 5, 1923. Serial No. 649,690.

To all whom it may concern:

Be it known that I, JAMES CHANTRY, of 638 Barnsley Road, Sheffield, in the county of York, England, a subject of the King of 5 Great Britain and Ireland, have invented certain new and useful Improvements in and Relating to Sharpening Devices, of which the following is a specification.

This invention relates to devices for 10 sharpening knives, razors and the like.

The object of my invention is to provide an improved device embodying the principle of the knife against the "steel" and for 15 enabling the knife or the like to be set at the correct angle to the "steel" or sharpening medium.

According to this invention a device for 20 sharpening knives, razors and other articles having a cutting edge, comprises a base, an upstanding pivot fixedly secured to said base at right angles thereto, a sharpening medium resiliently mounted on said pivot and oscillatable over the base in a plane parallel thereto, and a support on the base 25 disposed in a plane parallel thereto for holding an article in the operable position between the sharpening medium and the base.

Referring to the drawings filed herewith:

Fig. 1 is a perspective view of one form 30 of device made in accordance with this invention.

Fig. 2 is a detail sectional view of a modification of the pivoted sharpening medium.

Fig. 3 is a similar view showing a further 35 modification.

Fig. 4 is a detail view showing modified forms of grooves for positioning the knives.

Fig. 5 is a perspective view of the base 40 with alternative devices for positioning the knives.

a is a base of any suitable material and having on its upper face, any number of grooves *b*, *b* for supporting a knife *c* at the requisite angle against a sharpening medium *d* pivoted at one end of the base and in such a manner as to be adjustable in its height to suit different widths of blades. This is effected in the example shown through the medium of a spring *e* disposed 45 on the pivot pin *f* and bearing against the sharpening medium *d* and a washer *g* on the pivot pin, said washer being adjustable on the pin *f* through the medium of a lock nut *h* on a threaded portion of said pin. 50 This pivot pin is suitably secured to the base 55 in any convenient manner.

In operation, the blade of a knife is inserted in one of the grooves *b*, as shown, and the sharpening medium manipulated over it in a horizontal plane, that is by 60 moving the said sharpening medium radially about its pivot, which thereby sharpens the blade on one side. The blade is then inserted in another of the grooves so as to dispose the blade with its other or unsharpened side against the sharpening medium and the manipulation thereof is repeated whereby the blade is completely 65 sharpened.

Although I have illustrated a "steel" as 70 the sharpening medium, any other suitable medium, for example, a file, carborundum stick or other abrasive member, may be used.

Further, the sharpening medium can be pivoted in such a manner, say, for example, 75 in a universal swivel or ball joint *j* as shown in Fig. 2, that it can be rotated to constantly vary its circumferential contact with the knife or it may be pivoted in any other suitable manner to achieve the same object. 80

It is also to be understood that this improved device is applicable for the use of existing "steels" by having a pivoted and/or swivelling socket *k* for the reception of the point of an ordinary "steel" *m* which, when 85 manipulated as before described, effectively sharpens a knife or the like.

Fig. 4 shows a modification in the form of groove which may be employed, this being in the form of a double groove, the 90 one *n* being smaller to take knives too narrow for the larger groove *o*.

Any suitable form of handle or holder may be fitted to the "steel" or other sharpening medium and any number of grooves 95 may be provided.

In the form shown, two grooves are shown on both sides of the pivoted sharpening medium, the two on one side crossing the two on the other side, but one groove only, or 100 more than two grooves, may be provided as desired.

If desired, the base *a* may be provided with supports *p*, *p* as shown in Fig. 5 suitably shaped to position the knife, the blade 105 being supported at each of its ends or other convenient points.

Knives of all kinds, razors, scythes and in fact almost any tool having a cutting edge can be sharpened or dressed with a 110 device made according to this invention.

It is to be understood that any number

of either of the double or single grooves or both may be employed and that they may be disposed at any angle to the axis of the base or holder and where necessary, 5 said grooves may cross one another at any point.

What I claim and desire to secure by Letters Patent is:—

1. A sharpening device comprising a base, 10 an upstanding pivot fixedly secured to said base at right angles thereto, a sharpening medium resiliently mounted on said pivot and oscillatable over the base in a plane parallel thereto, and a support on the base 15 disposed in a plane parallel thereto for holding an article in the operable position between the sharpening medium and the base.

2. A sharpening device comprising a base, 20 an upstanding pivot fixedly secured to said base at right angles thereto, a sharpening medium resiliently mounted on said pivot and oscillatable over the base in a plane parallel thereto so that it may be moved 25 radially and circumferentially relatively to an article, and a grooved support on the base disposed in a plane parallel thereto for holding an article in the operable position between the sharpening medium and 30 the base.

3. A sharpening device comprising a base, an upstanding pivot fixedly secured to said

base at right angles thereto, an oscillatory sharpening medium resiliently and rotatably mounted about said pivot so that it 35 may be passed over an article in a plane parallel to the base, and a grooved support on the base disposed in a plane parallel thereto for holding an article in the operable position between the sharpening me- 40 dium and the base.

4. A sharpening device comprising a base, an upstanding pivot fixedly secured to said base at right angles thereto, a sharpening medium resiliently mounted on said pivot and oscillatable over the base in a plane parallel thereto, and a support having co- 45 related grooves for holding articles of different widths in the operable position between the sharpening medium and the base. 50

5. A sharpening device comprising a base, an upstanding pivot fixedly secured to said base at right angles thereto, a sharpening medium resiliently mounted on said pivot and oscillatable over the base in a plane parallel thereto, and a grooved support on the base disposed in a plane parallel thereto for holding an article in the operable position between the sharpening medium and the base, and means for regulating the degree of resilience to said sharpening medium. 55

In testimony whereof, I affix my signature.

JAMES CHANTRY.
